UNITED STATES PATENT OFFICE.

SAM H. LIBBY, OF EAST ORANGE, NEW JERSEY, ASSIGNOR TO SPRAGUE ELECTRIC COMPANY,
A CORPORATION OF NEW JERSEY.

AUTOMATIC CARRIER.

No. 926,884.

Specification of Letters Patent.

Patented July 6, 1909.

Application filed August 7, 1905. Serial No. 273,017.

To all whom it may concern:

Be it known that I, SAM H. LIBBY, a citizen of the United States, residing at East Orange, county of Essex, State of New Jersey, have invented certain new and useful improvements in Automatic Carriers, of which the following is a specification.

My invention relates to automatic carriers of the type provided with a hoisting mechanism, adapted to raise a load to any desired height and then move it to a distant point, and the object of my invention is to simplify the control as far as possible, rendering it almost wholly automatic, and thereby increasing the convenience and efficiency of the carrier. I so arrange the carrier that when the operator has once started the hoisting motor to raise the load, no further attention is required on his part; but when the load reaches a predetermined height, the hoisting movement is stopped and the traversing motor is started automatically.

My invention consists in a carrier provided with a driving motor, a hoisting motor, a current-collecting device, a controlling switch for each motor adapted to connect it to said device, a height-limit device adapted to be actuated by the hoisting movement, and operative connections between the height-limit device and both switches so that the hoisting motor is stopped and the driving motor is started when the load reaches a predetermined height.

My invention further comprises means for automatically stopping and reversing the driving or traversing motor of the carrier when it has reached the limit of its travel.

My invention further comprises so arranging the controlling switches of the hoist as to adapt it for use in connection with the trolley system for automatic carriers disclosed in my Patent No. 816,484, March 27, 1906. In my former application I described a trolley system extending through a plurality of stations and comprising a continuous conductor and a sectional conductor, a carrier with collecting devices adapted to engage both conductors, a switch for connecting the driving motor to either collecting device, an electro-magnet for holding the switch in position to connect the motor to the continuous conductor, means at a point at the limit of travel of the carrier

for deenergizing the magnet so as to shift the switch to connect the motor to the sectional conductor, and means at the several stations for energizing the sections of the sectional conductor between that point and that station.

By my present invention, in place of the magnet winding for holding the switch in position to connect the motor to the continuous conductor, I so arrange the connections between the height-limit device and the controlling switch for the traversing motor that when the device is moved, the switch is shifted to connect the motor to the continuous conductor, and I provide means at the limit of travel for disengaging the switch from the height-limit device, so as to allow it to return to a position to connect the motor to the sectional conductor.

My invention will best be understood by reference to the accompanying drawing, in which—

Figure 1 shows a side elevation of an automatic carrier arranged in accordance with my invention, and Fig. 2 shows diagrammatically the circuit connections and arrangement of the carrier and of the trolley system.

In the drawing B represents a bucket or other receptacle suspended from the hook H, which in turn is suspended from the hoisting drum D driven by the hoisting motor M¹.

M¹ is the driving or traversing motor of the carrier, and is connected through suitable speed-reducing gears G to the driving wheels 90 of the carrier which roll on the track T, which is indicated as of the usual I-beam form.

C² represents the controller for the motor M², only the operating shaft of this controller being shown in Fig. 1. The controller is provided with suitable ropes h and l, by means of which the controller may be moved to hoisting and lowering positions.

c² represents the height-limit device which in the form shown consists of an arm extending into the path of travel of the hook H. The connection between the height-limit device and the controlling switches is clearly shown in Fig. 2, in which the position of the arm c², when the controller C² is in the hoisting position, is indicated in dotted lines. When the load reaches a predetermined height the hook shifts the arm to the position shown in full lines. This arm c² is fast to the shaft of the controller C², and consequently

shifts the controller, to the position shown, which is the off-position. Thus, the circuit of the motor M^2 is broken and the hoisting movement stopped. The height-limit device 5 c^2 is connected by a link c to an arm e , which is loosely mounted on the shaft of the controlling switch C^1 of the traversing motor. Pivoted on the arm e is a second arm E . The two arms E and e are drawn together by 10 tension-spring e^1 . The arm E consequently bears against a cam c^1 , which is fast to the shaft of the controller C^1 . The cam c^1 is provided with a projection, as shown, which in the position shown is engaged by the arm E . 15 Consequently, the movement of the height-limit device c^2 has rotated the controller C^1 from one of its operative positions to the other. The spring F tends to return the switch C^1 to its other position when released 20 or disengaged from the height-limit device. R represents a stop placed along the line of way at the limit of travel provided with a hinged projection r adapted to be engaged by the arm E . When the arm E strikes this 25 stop it is moved on its pivot against the tension of spring e^1 , so as to release the cam c^1 and allow the spring F to return the switch C^1 to its other position. As will be here- 30 after seen, this results in reversing the traversing motor so as to start it back in the reverse direction. The projection r is hinged on the stop R to allow the arm E to pass under it freely when the carrier is moved in the reverse direction. 35 Now, considering the trolley system for supplying the carrier, it will be seen that there are three working conductors engaged by the collecting device t^1 , t^2 , and t^3 respectively. The conductor X is of one polarity, 40 and the other two conductors are of the opposite polarity. The conductor X is connected to both motors through the collecting device t^1 . If a ground return is used, this conductor would be omitted. Of the other 45 two conductors which are of opposite polarity to that of conductor X , one, Y , is continuous, while the other is made up of normally unenergized insulated sections, which are indicated by the letters Z , Z^1 , Z^2 , etc., corre- 50 sponding to a plurality of stations served by the carrier. At each station is placed a switch S^1 , S^2 , etc., which when depressed connects all the sections of the sectional conductor to the right of the station to the 55 continuous conductor Y . The operation is then as follows: assuming that the hoisting motor M^2 has been operating so as to raise the load to shift the height-limit device to the position shown in Fig. 2, 60 the controller C^2 has been shifted to off-position, and the controller C^1 has been shifted to the position shown. A circuit is now closed from the working conductor Y through collecting device t^2 , switch C^1 , armature of motor 65 M^1 , switch C^1 , field of motor M^1 , collecting

device t^1 , to conductor X . The circuit of the motor M^1 is thus closed and the motor starts, driving the carrier toward the right, as viewed in Fig. 2. The carrier continues to run until the point is reached at which the load is 70 to be dumped. At this point stop G is placed, adapted to engage the bucket B and to tip it to discharge the load. At or beyond this point is placed the stop R , which, as has been heretofore explained, engages the arm E , and thereby releases the switch C^1 from the height-limit device, allowing it to return to its other operative position. A circuit is then 75 closed from section Z of the sectional conductor through trolley t^3 , through switch C^1 , 80 through armature of motor M^1 in the reverse direction, through field of motor M^1 , to trolley t^1 , to conductor X . The motor is thus connected to conductor Z , instead of conductor Y , and is also connected for rotation in the 85 opposite direction. The carrier consequently starts back and runs until the trolley t^3 leaves section Z and enters on section Z^1 . The circuit of the driving motor is then broken by trolley t^3 being on the unenergized section Z^1 90 and the motor stops. Now if the man at any one of the stations served by the carrier, as for instance station 3, wishes to bring the carrier to him, he depresses his switch S^3 and holds it down. Sections Z^1 , Z^2 and Z^3 of the 95 sectional conductor are then connected to conductor Y , so that the driving motor is again energized and drives the carrier until station 3 is reached, at which point the trolley t^3 runs on to the dead section Z^4 and the 100 carrier stops. The operator may now pull down on rope l , moving the controlling switch C^2 to lowering position, so that the bucket will be lowered to receive another load. As the bucket is lowered, the hook H moves 105 away from the arm c^2 , so that when the bucket has been filled it may again be raised by drawing down upon the rope h . With the carrier arranged as above de- 110 scribed, it is evident that no attention is required from the operator after the hoisting motor has been started. The buckets are automatically stopped at the proper height to be engaged by the stop G at the limit of travel, and the traversing motor is started as 115 soon as the load has reached the proper height.

I do not desire to limit myself to the particular construction and arrangement of parts here shown, but aim in the appended 120 claims to cover all modifications which are within the scope of my invention.

What I claim as new, and desire to secure by Letters Patent of the United States, is,--

1. In an automatic carrier, a driving motor therefor, hoisting mechanism carried thereby, a current-collecting device carried by the carrier, and means actuated by the hoisting mechanism for automatically connecting said driving motor to said current 130

collecting device independently of the position of the carrier.

2. In an automatic carrier, a driving motor therefor, hoisting mechanism carried thereby, a current-collecting device carried by the carrier, and means mounted on said carrier and actuated by the hoisting mechanism for automatically connecting said driving motor to said current-collecting device independently of the position of the carrier.

3. In an automatic electrically-driven carrier, a hoisting motor, a traversing motor, a height-limit device, a control switch for the hoisting motor and a reversing switch for the traversing motor, both of said switches controlled by said device.

4. In an automatic electrically-driven carrier, a traversing motor, a hoisting motor, a reversing switch in circuit with each motor, a member adapted to be engaged by the hoisting mechanism, and operative connections between said member and both switches.

5. In a carrier system, a plurality of stations, a carrier, a hoisting motor, a traversing motor, means operated by the hoisting movement for automatically stopping the hoisting motor and starting the traversing motor, means for automatically reversing the traversing motor at a predetermined point in its travel, and means for stopping the carrier in its return movement at any one of said stations.

6. In a carrier system, a plurality of stations, an electrically-operated carrier, a hoisting motor, a traversing motor, two working conductors extending past all of said stations, one of said conductors being continuous and the other interrupted at each station, means operated by the hoisting movement of the carrier for automatically breaking the circuit of the hoisting motor and connecting the traversing motor to the continuous conductor, means for reversing said traversing motor at a predetermined point in its travel and connecting it to the sectional conductor, and means at each station for energizing the sections of said conductor between said point and that station.

7. In a carrier system, an electrically-operated carrier, a hoisting motor, a traversing motor, a reversing switch for each motor, means actuated by the hoisting movement for moving the reversing switch of the hoisting motor to off-position and moving the reversing switch of the traversing motor to one operative position, and means for moving the latter reversing switch to its other operative position at a predetermined point in the travel of the carrier.

8. In a carrier system, an electrically-operated carrier, a hoisting motor, a traversing motor, a reversing switch for each motor, a height-limit device, operative connections

between said device and both switches, and means for automatically disengaging the reversing switch of the traversing motor from said device at a predetermined point in the travel of the carrier.

9. In a carrier system, an electrically-driven carrier, a reversing switch for the driving motor, a spring normally holding said switch in a certain position, hoisting mechanism carried by said carrier, a height-limit device actuated by said hoisting mechanism, operative connections between said device and said switch, and means for disengaging said switch from said device at a predetermined point in the travel of the carrier.

10. In a carrier system, a plurality of stations, a carrier, a driving motor, a hoisting mechanism carried by said carrier, a height-limit device actuated by said hoisting mechanism, means carried by the carrier and controlled by said device for starting said driving motor, and means for automatically reversing the driving motor at a predetermined point in the travel of the carrier and means for causing the return of said carrier to any one of said stations.

11. In a carrier system, a plurality of stations, an electrically-operated carrier, a controlling switch therefor, two working conductors extending past all of the stations, one of the conductors being continuous and the other interrupted at each station, a hoisting mechanism carried by the carrier, a height-limit device actuated by said hoisting mechanism, operative connections between said device and said switch adapted to move said switch to connect the driving motor of the carrier to the continuous conductor, means for automatically shifting said switch to reverse the motor and to connect it to the sectional conductor at a predetermined point in the travel of the carrier, and means at each station for energizing the sections of said conductor between said point and that station.

12. In combination, a motor-driven carrier, a trolley conductor, a collecting device carried by said carrier, a switch mounted on said carrier for closing the motor circuit through said collecting device, a hoisting mechanism carried by the carrier, a height-limit device actuated by said hoisting mechanism, and operative connections between said limit device and said switch for operating said switch when the hoisting mechanism reaches the upper limit of its travel independently of the position of the carrier.

13. In combination, a motor-driven carrier, a trolley system comprising two conductors, collecting devices carried by said carrier and engaging said conductors, a switch adapted to close the motor circuit through either of said devices, and a stop along the line of travel adapted to be engaged by said carrier when driven by current through one of said collecting devices and to shift said

switch to close the motor circuit through the other collecting device and simultaneously to reverse the motor.

14. In combination, a motor-driven carrier, a trolley system comprising two conductors, collecting devices carried by said carrier and engaging said conductors, a switch adapted to close the motor circuit through either of said devices, and a stop along the line of travel adapted to be engaged by said carrier when driven by current through one of said collecting devices and to shift said switch to disconnect the motor circuit from that collecting device and to connect it to the other.

15. In combination, a motor-driven carrier, a trolley system comprising two conductors, one continuous and the other sectional, passing through a plurality of stations, col-

lecting devices carried by said carrier and engaging said conductors, a switch adapted to close the motor circuit through either of said devices, a stop along the line of way adapted to be engaged by said carrier when driven by current from said continuous conductor and to shift said switch to connect the motor circuit to the sectional conductor and simultaneously to reverse the motor, and means at each station for energizing the sections of said conductor between said stop and that station.

In witness whereof, I have hereunto set my hand this second day of August, 1905.
